A. PAPINI.
COMPRESSIBLE RHEOSTAT.
APPLICATION FILED MAR. 23, 1920.

1,343,472.

Patented June 15, 1920.

UNITED STATES PATENT OFFICE.

ANTONIO PAPINI, OF PHILADELPHIA, PENNSYLVANIA, ASSIGNOR TO A. MECKY COMPANY, OF PHILADELPHIA, PENNSYLVANIA, A CORPORATION OF PENNSYLVANIA.

COMPRESSIBLE RHEOSTAT.

1,343,472.

Specification of Letters Patent. Patented June 15, 1920.

Application filed March 23, 1920. Serial No. 368,020.

To all whom it may concern:

Be it known that I, ANTONIO PAPINI, a subject of the King of Italy, and having resided in the United States one year last 5 past, and having declared my intention of becoming a citizen thereof, residing in the city and county of Philadelphia, State of Pennsylvania, have invented a new and useful Compressible Rheostat, of which the following is a specification.

My invention consists of a novel construction of a double cell rheostat which is designed to step down the current of the house lighting circuit to the proper point so that 15 said current can be used in connection with bells, audible signals and the like, my novel device being provided with novel adjustable devices, so that it may be adjusted to take care of one bell or a plurality of bells.

20 My novel rheostat is designed to be fastened or supported upon a wall, board or other support, and its general principles of operation embodies the compression of conducting and non-conducting substances commingled together, as mica and graphite or graphite and asbestos or the like, said substances being comminuted or commingled in suitable proportions and the compression taking place in a plurality of separate cylinders contained within a porcelain body, said cylinders containing pistons which are operable or adjustable in unison.

It further consists of a novel construction of a rheostat, comprising a cover or body of porcelain or the like, within which cylinders are formed, said cylinders containing porcelain or other pistons, which have a connecting plate common thereto, said plate having a threaded stem passing there- 35 through and being held in proper position by a suitable tension device.

It further consists of a novel construction of a bottom closure and its adjuncts for the bottom of the transformer wherein the bottom of the porcelain body is provided with means for insulating and retaining said closure in proper position with respect to said bottom.

It further consists of a novel construction 50 of a bottom closure having integral eyes, struck up therefrom and rods or pins passing through said eyes and having their ends seated in the walls of the rheostat body.

It further consists of other novel fea-

tures of construction all as will be herein- 55 after fully set forth.

For the purpose of illustrating my invention, I have shown in the accompanying drawings one form thereof which is at present preferred by me, since the same will be 60 found in practice to give satisfactory and reliable results, although it is to be understood that the various instrumentalities of which my invention consists can be variously arranged and organized and that my 65 invention is not limited to the precise arrangement and organization of these instrumentalities as herein shown and described.

Figure 1 represents a vertical sectional view of a rheostat embodying my invention, 70 the section being taken on line 1—1 of Fig. 2.

Fig. 2 represents a section on line 2—2 of Fig. 1.

Fig. 3 represents a top plan view of 75 Fig. 1.

Fig. 4 represents in detached position a perspective view of a connecting plate employed, the same being shown in detached position from its coating pistons. 80

Fig. 5 represents a perspective view of the bottom plate or closure in detached position.

Similar numerals of reference indicate corresponding parts in the figures.

1 designates my novel construction of a 85 rheostat, all the internal mechanism thereof being contained within a cover or body of porcelain or the like 2, which is composed of the top 3 and depending walls 4, the bottom of said body being initially left open while 90 from about the center of said top depends the preferably integral wall or portion 5, having the bore or passage 6 therethrough, in which is seated the screw 7, whose head 8 is contained in the countersunk portion 9. 95 Within the cover 2 are formed two cylinder bores or piston chambers 10 closed at their top and open at their bottom and as the construction of each and their adjuncts is substantially the same, a description of one will 100 suffice for both. At the upper extremity of each piston chamber, cell or bore 10, I locate the contact plate 11, against which contacts the resistance material 12 which latter is contained between said plate 11 and the piston contact plate 13 which is carried by the porcelain piston 14. The piston contact plate 13 has an asbestos washer 15 interposed be-

tween it and the piston 14, and said plate, washer and piston are held in assembled position by the screw 16. 17 designates an insulating washer, and the parts 13, 14, 15 and 17 are held in position by the nut 18, said screw and nut also serving as a binding post for the lead wire 19 shown in Fig. 2, but omitted from Fig. 1, for the sake of clearness of illustration.

20 designates a compressing plate composed of the straight members 21, having the holes 22 therethrough, through which the screws 16 pass, and in the intermediate bowed or depressed portion 23 having the hole 24 therethrough which may be tapped or threaded, through which passes the lower threaded portion of the central screw 7, it being apparent that the coiled spring 25, seen in Fig. 1 and interposed between the top of the depressed portion 23 and the bottom of the wall 5, will exert the proper tension upon said plate 20 at all times and that as the screw 7 is rotated the position of the pistons 14 and the extent of compression on the material 12, may be readily varied, as desired.

The compressing plate 20 is properly insulated from the binding posts 16 by the washers 17.

26 and 27 designate conductors, whose terminals as 28 and 29 are connected electrically to the contact plates 11, the manner of such connection being apparent from the right of Fig. 3 and the upper left hand portion of Fig. 2, the loop 29 being soldered to the plate 11. At the lower right of Fig. 2 is shown the preferred connection of the terminal of the wire 19 to its binding post 16, the terminal portion 30 being soldered to the washer 31. The open bottom of the cover or body 2 has the shoulder 32 against which is secured the paper or other insulating material 32, which is held in place by the bottom closure 33 of metal or similar material; said closure having the punched or sheared loops struck up therefrom forming the eyes 34, which may be four in number, as will be understood from Fig. 5 through which pass the pins 35 whose outer ends are seated in holes 36 in the walls 2.

As will be understood from Fig. 2, the pins 35 are shorter than the outer dimensions of the case or body 2 and the outer portions of said holes 36 are filled with cement 37.

The foregoing construction forms a neat and efficient closure for the bottom of the rheostat body, since it effectively seals and closes the same, as is evident.

60 The slotted lugs 38 form a convenient means for securing the rheostat in the desired position, and the recesses 39 whose location in the base of the rheostat will be understood from Figs. 1 and 2 are for ventilation purposes.

It will be seen from the foregoing that by adjusting the screw 7, the compression of the material 12 can be varied according to requirements, through the medium of the plate 20 and the pistons 14 and their adjuncts, any desired adjustment of said screw being readily made by the insertion of a suitable implement through the countersunk hole 9 in the top of the device it being apparent that the resistance of the material 12 will be varied, according to its compression effected by the adjustment of the pistons 14.

The double cell construction seen in Fig. 1 and the provision of the adjusting device above referred to, enable my novel rheostat to be readily adjusted to different voltages to take care of one bell or audible signal or a plurality thereof.

It will now be apparent that I have devised a novel and useful construction of a rheostat which embodies the features of advantage enumerated as desirable in the statement of the invention and the above description, and while I have, in the present, instance, shown and described a preferred embodiment thereof which will be found in practice to give satisfactory and reliable results, it is to be understood that the same is susceptible of modification in various particulars without departing from the spirit or scope of the invention or sacrificing any of its advantages.

Having thus described my invention, what I claim as new and desire to secure by Letters Patent is:

1. In a double cell rheostat, a porcelain body, having a plurality of piston chambers therein, a contact plate for the top of each of said piston chambers, a contact plate for each of said pistons and insulated therefrom, compressible resistance material between said plates, a compressing plate common to said pistons, an adjusting screw intermediate of said cylinders, and in engagement with said plate and a spring intermediate of said plate and the portion of said body in which said screw is mounted.

2. In a double cell rheostat, a porcelain body having a closed top, depending side walls and an open base, piston chambers in said body, pistons in said chambers, an adjusting screw mounted in said body intermediate of said pistons, a compressing plate common to said piston and in threaded engagement with said screw, and means interposed between said compressing plate and the portion of the body in which said screw is mounted for resiliently supporting said pistons and compressing plate.

3. In a double cell rheostat, a porcelain body having a closed top, depending side walls and an open base, piston chambers in said body, pistons in said chambers, an adjusting screw mounted in said body intermediate of said pistons, and a compressing

plate common to said piston and in threaded engagement with said screw, in combination with a tension device for said plate.

4. In a double cell rheostat, a porcelain body having a closed top, depending side walls and an open base, piston chambers in said body, pistons in said chambers, an adjusting screw mounted in said body intermediate of said pistons, and a compressing plate common to said piston and in threaded engagement with said screw, in combination with a closure for said open base, eyes on the inner surface of said closure, insulating material above said closure, and pins passing through said eyes and seated in holes in said walls.
5. In a double cell rheostat, a porcelain body having a closed top, depending side walls and an open base, piston chambers in said body, pistons in said chambers, an adjusting screw mounted in said body intermediate of said pistons, a compressing plate common to said piston and in threaded engagement with said screw, in combination with a tension device, pressing outwardly on said plate, a closure for said open base, eyes on the inner surface of said closure, insulating material above said closure, pins passing through said eyes and seated in holes in said walls and a cement filling for the outer ends of said holes.

6. In a double cell rheostat, a body, a plurality of cells therein, compressible resistance material therein, means for varying the compression on said resistance material, 35 a closure for the bottom of said body comprising a plate having eyes on its inner surface, insulating material on said plate, pins passing through said eyes and having their ends seated in holes in said body and closing 40 means for said holes.

7. In a double cell rheostat, a plurality of cells, compressible resistance material therein, contact plates above and below said resistance material, a threaded screw intermediate of said cells, a compressing plate actuated by said screw, and resiliently supported connections from said plate for varying the compression of said resistance material. 45

8. In a double cell rheostat, a body, a cell therein containing resistance material, means for compressing the latter, and a closure for the bottom of said body, comprising a plate having eyes therein, pins passing through 55 said eyes and having their ends seated in holes in said body and a cement filling for the outer ends of said holes.

ANTONIO PAPINI.
